UNITED STATES PATENT OFFICE.

SAMUEL M. CURWEN, OF HAVERFORD, PENNSYLVANIA, ASSIGNOR TO
JOHN A. BRILL, OF PHILADELPHIA, PENNSYLVANIA.

GRAB-HANDLE FOR RAILWAY-CARS.

SPECIFICATION forming part of Letters Patent No. 784,519, dated March 7, 1905.

Original application filed September 6, 1904, Serial No. 223,544. Divided and this application filed December 17, 1904. Serial No. 237,224.

To all whom it may concern:

Be it known that I, SAMUEL M. CURWEN, a citizen of the United States, and a resident of Haverford, Montgomery county, State of Pennsylvania, have invented certain new and useful Improvements in Grab-Handles for Railway-Cars, of which the following is a specification.

The present application is a division of an application filed by me on the 6th day of September, 1904, and serially numbered 223,544.

In the class of cars known as "open" or "summer" cars, in which the passengers enter and leave through the side of the car between the seats, numerous accidents occur by reason of the passenger facing the wrong direction.

It is the object of my invention to so dispose and operate the grab-handle that its position will encourage the passenger to face in the direction of the car when leaving by disposing the handle in such place that he will only be able to use the one in front of him.

The details of construction and operation of my invention will be hereinafter more fully explained.

In the drawings forming a part of this specification, Figure 1 is a side elevation of the car post and seat, together with my improved grab-handle. Fig. 2 is a cross-section 30 of the line 22 of Fig. 1 looking downwardly.

But one car post and seat is shown, as it is understood that in the class of car to which my invention is applied the passengers enter and leave between the stanchions and between the car-seats, and as my invention may be applied to any car of this class further illustration is believed to be unnecessary.

By disposing the grab-handle of the car a short distance to the rear of the stanchion a passenger leaving from the aisle immediately behind such stanchion is induced to grab that handle, especially as it will be almost impossible to grab the handle on the stanchion at his rear, and by making the grab-handle to operate with the swing of the car-seat back the position of the handle is reversed when the seats are turned preparatory to the return-trip.

In the drawings I have shown a car-stan-

chion 1, which may be of any of the desired forms, and a car-seat 2, which rests between the stanchions on each side of the car. Any suitable seat-back 3 is provided and is carried by arms 4, which are pivoted to the car-stanchion on a pin 5, which passes through the stanchion. At the outer end and preferably made integral with this pin 5 is an arm 6, which is adapted to move in unison with the seat, arm 4 being secured thereto. The grab-handle consists of an upright rod 7, of proper length, and is provided with arms extending laterally from the stanchion. In the construction which I have used I have employed an upper arm 8, which is fulcrumed to a stud 9 in the post and also fulcrumed at the point 10 on the bar 7. Another arm, 11, is likewise fulcrumed below at the points 12 and 13. A central arm 6 is similar to the arms 8 and 11 and is likewise fulcrumed at the point 14 to the bar 7, the opposite end being connected to the pin 5, as previously described. A suitable rest 15 is attached to the stanchion below the arm 6, which forms a rest for the latter when it is in either one of the horizontal positions shown in the drawings. When the parts are in the position shown in the full lines of Fig. 1, the handle is adapted to be used from the side exit at the rear of the seat-back, and when the car reaches its destination or wherever it is desired to change its direction the seat-back 3 is swung over on its arm 4, and by reason of its connection with the arm 6 causes all three arms 6, 8, and 11 to move in a vertical arc, as indicated in the drawings, until the rod 7 is brought into the position shown in dotted lines, when both the seat and the grab-handle are adapted to be used from the opposite direction.

Having described my invention, what I claim is—

1. A railway-car having side posts or stanchions, side openings between the stanchions, a grab-handle comprising a vertical hand-rod fulcrumed to an arm, which arm is fulcrumed to the stanchion, whereby said rod may swing on said arm, and means for holding the said rod in predetermined positions in relation to said stanchion.

2. A railway-car having side posts or stanchions, side openings between the stanchions, seats between said stanchions having a movable back, a grab-handle fulcrumed to arms which are also fulcrumed to said stanchion, and means whereby the movement of said seat-back will move said arms in a vertical arc to alter the position of said grab-handle in its relation to said stanchion.
3. A railway-car having stanchions, side openings between the stanchions, a seat between said stanchions having a movable back carried by an arm, a grab-handle fulcrumed to an arm which is connected with the arm of said back, whereby the arm of the grab-handle will be moved in a vertical arc thereby.
4. A railway-car having side posts or stan-

chions, side openings between the stanchions, seats between the stanchions, swing seat-backs pivoted to the stanchion, having a pivoting-pin extending through said stanchion and a grab-handle fulcrumed to arms which are also fulcrumed to the stanchion, one of said arms engaging with the pivoting-pin of said seat-back whereby the movement of the seat-back will cause the said arm to move in a vertical plane, and a rest for the arm of said grab-handle.

Signed this 21st day of November, 1904.

SAML. M. CURWEN.
